UNITED STATES PATENT OFFICE.

HARRY W. PIERCE, OF WAVERLEY, MASSACHUSETTS.

SHADE-ATTACHING CLIP OR CLAMP.

1,200,977.

Specification of Letters Patent. Patented Oct. 10, 1916.

Application filed December 15, 1915. Serial No. 66,940.

To all whom it may concern:

Be it known that I, HARRY W. PIERCE, a citizen of the United States, residing at Waverley, in the county of Suffolk, State 5 of Massachusetts, have invented a new and useful Shade-Attaching Clip or Clamp; and I do hereby declare the following to be a full, clear, and exact description of the invention, such as will enable others skilled 10 in the art to which it appertains to make and use the same.

This invention relates to an improved shade attaching clip or clamp for shade rollers, and an object of the invention is to 15 provide an attaching clip or clamp of this nature, for detachably securing the shade to the roller, without materially injuring the attached portion of the shade.

Another object of the invention is to provide 20 a shade attaching clip or clamp for shades, awnings, wall maps, or like articles that are suspended from a roller or the like, so as to hold any one of such articles to its roller in such wise as to eliminate the use of 25 tacks, brads or similar fasteners.

Another object of the invention is to provide 30 a device of this nature in which improved features of construction are involved.

One of the features of the invention is the 35 provision of an elongated plate partially curved in cross section to conform to the contour of the shade roller and having means on or adjacent to one of its edges for securing the plate to the roller, while 40 the opposite edge of the plate terminates in annular arms adapted to extend nearly about the cylindrical contour of the roller, said arms terminating in spurs, to secure the arms of the roller.

Another feature of the invention is to provide 45 the plate with transverse stiffening ribs curved in cross section, and from which the ribs the arms merge, which are likewise curved in cross section, to insure rigidity of the arms, and yet at the same time allow resiliency.

Another feature of the invention is the provision of spurs struck up from the plate, and which are of sufficient length to merely 50 pierce the shade.

In practical fields the details of construction may necessitate alterations, falling within the scope of what is claimed.

The invention comprises further features 55 and combination of parts, as hereinafter set forth, shown in the drawings and claimed.

In the drawings: Figure 1 is a view in perspective of a shade roller, showing the application of the shade attaching clip. Fig. 2 is an enlarged detail perspective view 60 of the attaching clip. Fig. 3 is an enlarged detail perspective view of the attaching clip, showing the same inverted to that shown in Fig. 2. Fig. 4 is a sectional view on line 4—4 of Fig. 1. Fig. 5 is a sectional 65 view on line 5—5 of Fig. 1.

Referring to the drawings, 1 designates an elongated plate, which is curved in a cross section, so as to fit the curvature of the cylindrical shade roller. The plate is 70 provided with a pair of stiffening ribs 2 extending transversely of the plate and being curved in cross section, so as to insure rigidity. These ribs 2 merge from one edge of the plate into annular arms 3, which are 75 curved in cross section, and extend almost to the opposite edge of said plate, thereby extending nearly around the roller. The arms 3 terminate in spurs or pointed lugs 4, designed to be driven into the shade roller, 80 thereby securely anchoring the arms. The plate 1 adjacent one of its edges is provided with large spurs 4^a, adapted to penetrate the roller, to secure the plate firmly to the roller, while the spurs 4 constitute means to secure 85 the arms 3 to the roller. The spurs 4^a also penetrate the shade adjacent its upper edge, thereby preventing the shade from being pulled out from between the roller and the clamp. In this manner the clamp and the 90 shade are securely fastened to the roller, particularly owing to the arms 3 acting to hold the other side of the plate in position. Struck up from the plate 1 are spurs 7 of 95 such length as to pass only through the curtain or shade 8, that is, when the plate is fastened to the roller to fit its contour, thereby assisting in securely holding the shade or curtain fastened. In fastening the shade, the entire length of the arms 3 are 100 passed through the shade adjacent its edge, and the part of the shade between the incision made by the arms 3 is pressed against and perforated by the short spurs 7 of the concaved surface of said plate 1. When 105 connecting the shade to the roller, the shade is arranged in its proper position, after which, by springing the arms 3 back, they are passed through the shade adjacent its upper edge, as shown, after which the spurs 110 4^a are driven through the shade near its edge and into the roller. The plate 1 is then

forced toward the shade and the roller causing the spurs to penetrate the shade, after which the arms 3 are drawn firmly about the roller and closely in contact therewith, after which the spurs 4 are driven into the roller.

5 The invention having been set forth, what is claimed as new and useful is:—

10 An attaching clip or clamp for shades and the like, comprising an elongated plate curved in cross section to fit the curvature of the shade roller and having spurs to pierce the shade, said plate on or adjacent one edge thereof having spurs to penetrate the roller to securely hold said edge to the roller, said plate adjacent its opposite edge merging into annular arms extending around the roller nearly to the opposite edge of the

15 plate, said arms at their terminals being provided with spurs to penetrate the roller, which together with the spurs adjacent said edge act to anchor the clip or clamp to the roller, said plate having transverse ribs curved in cross section and merging into said arms, which are likewise curved in cross section substantially throughout their 25 length.

In testimony whereof I have signed my name to this specification in the presence of two subscribing witnesses.

HARRY W. PIERCE.
